[57] CLAIM

The ornamental design for a foam pad, as shown and described.

DESCRIPTION

FIG. 1 is a perspective view of a foam pad showing the surface pattern of my new design, the actual configuration being shown in FIG. 4 and the undisclosed bottom being plain and unornamented;

FIG. 2 is an end elevational view thereof, the opposite end being a mirror image of that shown;

FIG. 3 is a side elevational view thereof, the opposite side being a mirror image of that shown; and

FIG. 4 is a vertical cross-sectional view thereof, taken along line 4—4 of FIG. 1.
